C. L. BETTS.
LANTERN GUARD.
APPLICATION FILED JUNE 29, 1908.

923,483.

Patented June 1, 1909.

UNITED STATES PATENT OFFICE.

CHARLES L. BETTS, OF NEW YORK, N. Y., ASSIGNOR TO R. E. DIETZ COMPANY, OF NEW YORK, N. Y.

LANTERN-GUARD.

No. 923,483.

Specification of Letters Patent.

Patented June 1, 1909.

Application filed June 29, 1908. Serial No. 440,933.

To all whom it may concern:

Be it known that I, CHARLES L. BETTS, a citizen of the United States, residing at New York, borough of Brooklyn, in the county of 5 Kings and State of New York, have invented a new and useful Improvement in Lantern-Guards, of which the following is a specification.

This invention relates mainly to that class 10 of tubular lanterns which are provided with a guard frame of basket form to which the lantern top is hinged for introducing and removing the globe and which are provided with a removable oil pot, as in ordinary railroad 15 lanterns.

The object of this invention is to provide the lantern with reliable and convenient means for locking the hinged top and the removable oil pot in position so that the flame 20 is inaccessible to unauthorized persons.

In the accompanying drawings: Figure 1 is a side elevation of a tubular lantern provided with these improvements. Fig. 2 is a partly sectional elevation at right angles to 25 Fig. 1. Fig. 3 is a fragmentary perspective view showing the locking devices of the top and oil pot released. Fig. 4 is a fragmentary plan view of the lower portion of the locking devices in the locked position and on an enlarged scale. Fig. 5 is a similar view showing the locking devices released. Fig. 6 is a 30 fragmentary side elevation of the lower portion of one of the air tubes and connecting parts of the bottom, showing a modified construction of the guard wire below the tube. Fig. 7 is a perspective view of the guard wire 35 detached.

Like reference characters refer to like parts in the several figures.

40 A represents the oil pot and B the body hoop or lower ring of the lantern frame into which the oil pot is inserted from below and to which the oil pot is detachably secured by a spring fastening or bayonet catch of such 45 construction that the oil pot is given a partial rotation in the body hoop B for engaging the oil pot with the spring fastening or disengaging it therefrom. The spring fastening shown in the drawings is of well known construction and comprises a spring catch 10 on 50 the body hoop and a stud 11 on the oil pot.

C represents the air tubes which are secured at their lower ends to the body hoop B and open through the same into the chamber

12 within the body hoop from which the 55 burner 13 is supplied with air. These tubes extend upwardly to about the level of the upper guard ring 14. D represents the lantern top which is connected with this guard ring by a hinge 15 at the rear side and a 60 spring catch 16 at the front side of the lantern in a well known manner, so that the globe E can be introduced into the guard from above.

F represents the metallic chimney which 65 is arranged within the top D and bears upon the globe so as to hold the latter on its seat in the body hoop.

The hinged top D comprises a cylindrical wall 17 forming the outer wall of the upper 70 air chamber, a horizontal base flange or plate 18, and elbows 19 which extend from the cylindrical wall outwardly and downwardly through the flange 18 and register with the open upper ends of the tubes when the top 75 is closed down upon the guard.

20 represents the bottom guard ring and 21 represents the upright main guard wires or members which are arranged between the tubes and extend from the top ring 14 to 80 the bottom ring 20 and are secured at the waist of the lantern with their inturned portions to the body hoop.

22, Figs. 1 and 2, represent short supplemental upright guard members or wires 85 which extend from the lower portions of the air tubes down to the bottom ring 20 and are provided at their upper ends with hooks or bent ends which are inserted into the tubes through openings in the under side of 90 the latter and rigidly secured therein by the tinning operation which is employed for finishing the frame. If preferred, these supplemental members may be constructed, as represented in Figs. 6 and 7, by doubling 95 a wire 23 upon itself and bending the lower end 24 of the doubled wire around the bottom ring 20, and spreading the upper ends 25 of the doubled wire to straddle the air tube. In either construction the supplemental member is connected with the air tube in such manner that these parts steady 100 each other.

The rigid lantern frame comprises the body hoop B, the air tubes C, the top guard 105 ring 14, the bottom guard ring 20, the main upright guard members 21 and the auxiliary guard members 22 or 23, and also preferably

an intermediate guard ring 26 which is secured to the main guard members 21 and the air tubes.

When lanterns of this kind are used by 5 watchmen it is often desirable to lock the top and the oil pot to the guard frame so that access cannot be had to the flame while the lantern is in use. The devices applied to the lantern for that purpose are constructed 10 to ed as follows:

27 represents a hasp, shackle or link which is movably connected at its upper end 28 to the lantern top, preferably the flange 18 thereof, and which extends downwardly 15 along one of the main guard members 21 to a point opposite the oil pot. This hasp is preferably composed of two similar parts which are arranged on opposite sides of the adjacent guard member and bent from a 20 single length of wire together with a finger piece 29 at the lower end of the hasp. This finger piece straddles the lower portion of the adjacent fixed guard member when the lantern top is closed, as represented in Figs. 25 2 and 4.

30 represents an eye or staple so arranged on the oil pot that when the latter has been secured in the lantern frame by the spring fastening or bayonet catch it stands near 30 the upright guard member with which the hasp 27 is engaged and is prevented by the hasp from being returned to the unlocked position. For locking the parts in this position the shackle 31 of a padlock 32 is passed 35 behind this guard member above the finger piece 29 thereof and preferably also through the eye 30 of the oil pot, as represented in Figs. 2 and 4. When the parts are so engaged with each other and locked by means 40 of the padlock the hasp is secured by the lock to the fixed guard member, whereby the lantern top is prevented from being raised, and the oil pot prevented from being turned in the body hoop to the position in 45 which it is released by the spring catch 10 and can be withdrawn from the body hoop.

Upon removing the padlock the hasp 27 can be disengaged from the fixed guard member and the lantern top can be raised, 50 as represented in Figs. 3 and 5, and the oil pot can be turned in the lantern body back to the position in which it is released by the spring fastening and can be withdrawn from the lantern body. In Fig. 5 the oil pot 55 stands in its unlocked position and must be moved in the direction of the arrow in order to reach the locked position, shown in Fig. 4, in which the eye 30 on the oil pot has passed by the fixed guard member 21 and 60 one branch of the hasp 27 has been engaged between the guard member and the eye and locks the oil pot against return movement to the unlocked position. It is preferred to 65 pass the shackle of the padlock through the eye and secure the latter to the fixed guard

member but, if desired, the eye may be used merely as a stop which is locked against return movement by the hasp, and in that case the stop need not have the form of an eye.

70 I claim as my invention:

1. In a lantern, the combination with a guard frame which is open at the top for the insertion of the globe and has its base portion provided with fixed upright members 75 which are arranged outside of the oil pot, and a lantern top hinged to the top portion of said frame, of a hasp which is movably connected at its upper end to said lantern top and adapted to be engaged at its lower end with one of the fixed upright members of the base portion of the guard frame, substantially as set forth.

2. In a lantern, the combination with a 85 guard frame which is open at the top for the insertion of the globe and is provided with fixed upright members, and a lantern top hinged to the top portion of said frame, of a hasp which is movably connected at its upper end to the lantern top and which comprises two upright branches which, when the hasp is engaged with one of the upright members of the guard frame, stand on opposite sides of such member, substantially as set forth.

90 3. In a lantern, the combination of a guard frame having upright members and an oil pot which is rotatable within said frame toward and from the locked position, a fastening for securing the oil pot in the locked position, a stop on said oil pot which stands adjacent to one of the upright guard members when the oil pot is in the locked position, and means for locking said stop to said member of the guard frame to prevent backward rotation of the oil pot to the unlocked position, substantially as set forth.

95 4. In a lantern, the combination with a 100 guard frame which is open at the top for the insertion of the globe, a lantern top hinged to such frame, and an oil pot which is rotatable in said frame toward and from the locked position, of a hasp which is movably connected at its upper end to the lantern top and which engages at its lower end one of 105 the guard members and at the same time secures the oil pot against rotation to the unlocked position, substantially as set forth.

110 5. In a lantern, the combination of a guard frame which is open at the top for inserting 120 the globe, a lantern top hinged to said frame, an oil pot which is rotatable in said frame toward and from the locked position, a hasp movably connected to the lantern top and adapted to be engaged at its lower end with 125 a fixed member of the guard frame and to be locked thereto, and a stop on the oil pot for interlocking the same with said fixed member against backward rotation to the unlocked position, substantially as set forth.

130

6. In a lantern, the combination of a guard frame which is open at the top for inserting the globe, a lantern top hinged to said frame, an oil pot which is rotatable in said frame
5 toward and from the locked position, a hasp movably connected to the lantern top and adapted to be engaged at its lower end with a fixed member of the guard frame and to be locked thereto, and a stop on the oil pot ar-
10 ranged to be held by said hasp and fixed guard member against backward rotation to the unlocked position, substantially as set forth.

Witness my hand in the presence of two subscribing witnesses.

CHARLES L. BETTS.
